ELECTRONIC COMMUTATOR

Clarence E. Frizzell, Poughkeepsie, N. Y., assignor to International Business Machines Corporation, New York, N. Y., a corporation of New York

Application November 18, 1952, Serial No. 321,156

17 Claims. (Cl. 250—27)

This invention relates to electronic pulse generating circuits and particularly but not exclusively to circuits for generating a sequence of pulses for switching or gating purposes in computing and similar apparatus.

It is sometimes required that periods of time must be subdivided into accurately determined time intervals, each interval being indicated by an electrical pulse. If the number of time intervals in each period of time is equal, the sub-division may be carried out by the use of a closed ring of bistable trigger circuits. The two conditions of stability of the triggers are designated as "on" and "off" conditions, and usually only one trigger in the ring is in the "on" condition. A master oscillator is used to generate pulses at a frequency equal to one pulse for each time interval. These pulses are applied to all the trigger circuits and their effect is to convert any trigger which is in the "on" condition to the "off" condition. The shifting of a trigger from the "on" to the "off" condition generates a potential variation which is fed to the next succeeding trigger to turn it "on." This progression or stepping of the "on" condition from one trigger to the next succeeding trigger may continue indefinitely since the triggers are connected in a closed ring. The period of time which is subdivided is equal to the pulse repetition rate of the oscillator multiplied by the number of trigger stages in the ring.

In some applications, it is required that certain periods have a different number of equal time intervals than others. For example, electronic computer systems utilizing devices for the storage of information may require less time for reading the information from the device than for writing the information. In such a case, it is desirable in order to save time, to have a lesser number of time intervals in the read period than in the write period.

Accordingly, it is an object of this invention to provide time intervals of various lengths and means for dividing those intervals.

Another object is to provide an electronic ring circuit including a series of bistable triggers to provide time division according to a prearranged pattern.

Another object is to provide an electronic ring comprising a chain of trigger circuits and including novel means to vary the effective number of trigger circuits in the ring.

It is a further object to provide a commutator circuit for distributing signals in a timed relationship and according to a prearranged pattern.

Another object is to provide an electronic ring comprising a chain of triggers and including coupling means for selecting different ones of said triggers for closing the chain.

Another object is to provide an electronic ring comprising a chain of triggers, means to count the number of cycles completed by the ring and means controlled by said counting means to change the effective number of triggers in the ring after a certain number of cycles have been counted.

2

Another object is to provide an electronic ring comprising a chain of triggers, means to count the number of minor cycles completed by the ring and means controlled by said counting means to change the effective number of triggers in the ring, a number of said minor cycles comprising a major cycle.

Other objects of the invention will be pointed out in the following description and claims are illustrated in the accompanying drawings which disclose, by way of example, the principle of the invention and the best mode, which has been contemplated, of applying that principle.

In the drawings:

Figs. 1 and 2 illustrate peaker circuits;

Figs. 3 through 6 illustrate trigger circuits;

Figs. 7 through 14 illustrate cathode follower circuits;

Figs. 15 through 18 illustrate switch circuits;

Figs. 19 through 23 illustrate inverter circuits;

Fig. 24 illustrates an oscillator;

Figs. 25, 26 and 27 taken together, as illustrated in

Fig. 34, constitute a complete block diagram of the invention;

Figs. 28 to 33 inclusive, assembled as illustrated in Fig. 35, constitute a complete timing diagram of signals emitted by certain lines of the devices of Figs. 25, 26 and 27; and

Figs. 36 and 37 are block diagrams illustrating how signals developed by Figs. 25, 26 and 27 may be used to develop other signals.

Wherever shown, unless otherwise indicated in the drawings, the values for the various resistors, inductances and condensers are in thousands of ohms, microhenries, and micro-microfarads, respectively. The term "positive" and "negative" potentials, used in the discussion of the circuits, refer to relative values rather than values with respect to ground.

In the novel apparatus of the invention, a timing ring consisting of bistable triggers is provided. As mentioned above, at least one trigger is in an "on" condition and the others are in "off" conditions. A master oscillator feeds pulses to all the triggers which step the "on" condition from one trigger to the next succeeding trigger. As the ring completes a cycle, a signal is emitted to a counter and after a predetermined number of cycles have been counted, the number of effective trigger stages in the ring is changed by including additional triggers or by excluding some triggers already in the ring. This change in the number of stages is accomplished by coupling the output of a certain designated stage of the chain of triggers, to several switch circuits. These circuits are selectively conditioned or not conditioned depending upon which outputs of which counters or control device is effective. The potential variation developed by the designated stage shifting from an "on" to an "off" condition is fed through a thus selectively conditioned switch circuit to restart the ring at a point in the ring varying with the switch selected for conditioning. As the ring completes a certain number of cycles, other switch circuits become conditioned and the ring is thus started at different trigger stages. As explained below, the signals emitted by the ring may be mixed with signals emitted by the counters to develop signals delineating different portions of the entire cycle.

Referring to the drawings and more particularly to Figs. 1 and 2, these circuits illustrate details of peaking circuits, designated P-1 and P-2. The circuit shown in Fig. 1 includes a pentode, which may be of the 5763 type, with a grounded cathode and a suppressor grid directly connected to the cathode. A circuit may be traced from the plate through two 50 millihenry coils connected in parallel, and a .047K resistor to a +150 volt power supply. The junction point of the 50 millihenry coils and the .047K resistor is grounded through an .05 microfarad con-

denser. An output terminal 6 is connected directly to the plate. The control grid is connected through an 0.1K resistor and a 10 micro-microfarad condenser to an input terminal 3 and through the same 0.1K resistor and a 300K resistor to the junction point of the 50 microhenry coils and the .047K resistor. The screen grid is connected through an 0.47K resistor to the same junction point. The pentode is normally conducting and is cut off by the negative swing of an input pulse applied to input terminal 3. As the tube cuts off, the 50 microhenry coils oscillate to produce an 0.2 microsecond pulse output at output terminal 6. A crystal diode, shunting the 50 microhenry coils serves to clamp the negative excursion of the oscillation signal so that only a single pulse output occurs, for each input pulse. The .047K resistor and the .05 microfarad condenser form a decoupling circuit so that the peaker, on being pulsed, will not draw a large slug of current from the +150 volt power supply. It is well-known by those skilled in the art, that the connections and value of the circuit components may be varied. In Fig. 2, for example, a 500 microhenry coil which is in the plate circuit is damped by a 3.6K resistor. A further difference over Fig. 1 is that the input condenser has a value of 470 microfarads. The output of Fig. 2 is an 0.5 microsecond pulse, for each input pulse.

Referring now to Figs. 3 through 6, these illustrate electronic triggers designated T-1 through T-5, all being of a type commonly known in the art as the Eccles-Jordan trigger. This type comprises two cross-coupled triodes in which the plate P-1 (Fig. 3) is cross-coupled by a 110K resistor in series with a .47K resistor to the grid G2 while the plate P2 is likewise cross-coupled to the grid G1 by a 110K resistor in series with a .47K resistor. Each of the 110K resistors is shunted by a 10 micro-microfarad condenser. Both the grids G1 and G2 are connected, through the .47K resistors, mentioned above, and 330K resistors, to a -250 volt power supply. The cathodes K are grounded while each of the plates P1 and P2 are connected through 3.9K resistors in series with 3.3K resistors to a power supply of +150 volts. Outputs are taken from terminal 7 connected directly to the plate P1 and from terminal 8 which is a tapped output on the plate resistors connected to P2. Inputs may be fed to the grid G1 from terminal 6 through an isolating diode, or to the grid G2 from terminal 3 to which is connected a differentiating circuit (comprised of a 20K grounded resistor and a 33 micro-microfarad condenser connected, as shown) and an isolating diode. The isolating diodes pass only negative signals.

If the left triode is conducting and a negative signal is applied to the terminal 6, the left triode is cut off. As the left triode stops conducting, the voltage at the plate P1 goes positive, which voltage, through the cross-coupling previously described, drives the grid G2 relatively positive so that the right triode conducts; thus P1 is positive while P2 is negative. This is one state of stability of the trigger which may be called the "off" or normal condition. In a similar manner, with the right triode conducting, the left triode may be rendered conductive, by the application of a negative pulse of suitable amplitude to the terminal 3, whereupon the right triode stops conducting and the voltage of P2 going positive is applied by the cross-coupling connection to the grid G1 causing the left triode to conduct, P1 becoming negative. This is the second state of stability which may be called the "on" condition.

The circuits shown in Figs. 4 through 6 are basically the same as the circuit of Fig. 3. The differences occur merely in the values of the circuit components, and the locations of the outputs (full or tapped plate resistor), or the use of differentiating circuits, on both inputs. One additional exception should be noted. In Fig. 4, there is an additional input terminal 5, which may receive a signal to turn the trigger on.

Figs. 7 through 14 illustrate the details of various

cathode follower circuits diagrammatically represented by blocks CF-1 through CF-4 and CF-6 through CF-9. Referring specifically to Fig. 7, block CF-1 specifically includes, a pentode having its plate connected through an .047K resistor to a +300 volt power supply and through an .05 micro-microfarad condenser to ground. The suppressor and screen grids are connected directly to the plate as shown. The control grid is connected through an 0.1K resistor and a 24K resistor to ground, through the same 0.1K resistor and a 240K resistor, to a power supply of -250 volts, and through the same 0.1K resistor and a 47 micro-microfarad condenser, to the input terminal 4. The cathode is connected directly to the output terminal 6 and through a 1K resistor to ground. The tube is normally cut-off, the application of a positive signal input causing a positive output in the cathode output terminal 6.

The CF-2 type, shown in Fig. 8, includes a dual triode, the triode sections operating in parallel. The plates are connected through an .047K resistor to a +300 volt power supply and through an .02 micro-farad decoupling condenser to ground. The grids are connected through separate .47K resistors and a common 240K resistor to a power supply of -250 volts, through the same .47K resistors and a common 24K resistor, to ground, and through the same .47K resistors and a common 47 micro-microfarad condenser, to an input terminal 4. The cathode is connected directly to the output terminal 6 and through a 0.1K resistor to ground. The tube is normally cut-off and is driven by the positive pulse output from the peaker P1 of Fig. 1 applied to its input 4. A plus output pulse is available at the terminal 6 for each positive pulse applied to the input terminal 4.

The CF-3 type, shown in Fig. 9, includes a dual triode with each half acting independently of the other identical half. Referring to the left triode, the plate is connected directly to a +300 volt power supply, the control grid is connected through a resistor to the input terminal 4 and the cathode is grounded through the series connected resistors of .2K, 6.8K and 3.9K. The output terminal 6 is tapped between the .2K and the 6.8K resistors. The right half is identical, except that terminal notations of 9 and 7 replace terminal notations of 4 and 6. As the grid of either half goes positive, the related output goes positive.

Fig. 10 shows a CF-4 type which includes a dual triode with both plates directly connected to a +150 volt power supply. The grids are connected through separate resistors and a common 300K resistor to a power supply of -250 volts and through the same separate resistors each in series with a common 150K resistor, to the terminal 9, the 150K resistor being shunted by a 22 micro-microfarad condenser. Each cathode is connected by a 4.7K resistor in series with a 2.2K resistor to a power supply of -100 volts.

The output terminals 6 and 7 are connected directly to the cathodes and both emit positive outputs when a positive signal is applied to the input terminal 9.

The CF-6 and CF-7 types, illustrated respectively in Figs. 11 and 12, are basically alike, differing from one another only in the values of the circuit components; therefore, explanation is made of Fig. 11 only. The plate of the left triode is connected directly to a +150 volt power supply, its grid is connected through a .47K resistor and a 330K resistor to a power supply of -250 volts and through the same .47K resistor and a 150K resistor to the input terminal 4, the 150K resistor being shunted by a 15 micro-microfarad condenser. The cathode is connected directly to an output terminal 6 and through a 6.8K resistor, in series with a 2.2K resistor, to a power supply of -100 volts. A positive input to terminal 4 causes a positive output at terminal 6. The circuit of the right half of the dual triode is identical with that just described, terminal 9 being the input and terminal 7 being the output.

The CF-8 type, shown in Fig. 13, differs from the CF-4 type, described above, only in values of certain components. A positive input to terminal 9 results in positive outputs at terminals 6 and 7.

Fig. 14 illustrates a CF-9 type. Referring to the left half of the dual triode, the plate is connected directly to a +150 volt power supply; the grid is connected through a .47K resistor in series with a 360K resistor to the same +150 volt power supply, through the same .47K resistor, in series with a 20K resistor, to ground and through the same .47K resistor, in series with a 47 micro-microfarad condenser, to an input terminal 4. The cathode is connected directly to an output terminal 6 and through two 2.2K resistors, respectively in series, to a -100 volt power supply. The input is condenser coupled and the circuit operates in class A. The right half is identical, with terminals labeled 9 and 7 correspond to the terminals labeled 4 and 6 of the left half.

Figs. 15 and 16 show switching circuits, designated respectively S1 and S2, that are identical, except for the value of an input condenser. Each circuit uses a pentagrid tube having a plate connected to an output terminal 7 and through resistors of 3.9K and 3.3K in series, to a power supply of +150 volts. The cathode and the number 5 grid are grounded. The number 2 and number 4 grids are connected together and through a resistor to the power supply of +150 volts. The number 3 grid is connected through a resistor, in series with a 510K resistor, to a power supply of -250 volts and through the same resistor and a 240K resistor, shunted by a 33 micro-microfarad condenser, to an input terminal 6. The number 1 grid is connected through a resistor and a 20K resistor to ground through the same resistor and a 240K resistor to a power supply of minus 250 volts, and through the same resistor either a 47 micro-microfarad condenser (as indicated in Fig. 15) or a 100 micro-microfarad condenser, as shown to an input terminal 3. The switches S-1 and S-2 operate as follows: The circuit may be "conditioned," by a positive input to terminal 6. A positive signal applied to the terminal 3 is differentiated by the input condenser and the associated resistor network so that only a sharp positive pulse reaches the grid. The tube conducts a short time only, that is for a time interval approximating the duration of the sharp pulse developed by the differentiated signal. Therefore, if the input to terminal 6 is positive and a positive signal (pulse or steady state voltage) is also applied to terminal 3, a negative pulse is available at the output terminal 7.

The switch S-4 shown in Fig. 17, is identical to switch S-2 except that the plate is not connected through plate resistors to a power supply. This switch is used to "pull" triggers to "on" or "off" conditions and is connected to the output terminal of a trigger in such a manner that the plate circuit of the trigger is also the plate circuit of the switch. Otherwise, switch S-4 operates in the same manner as switch S-2.

The switch circuit S-5 (Fig. 18) is also identical with the switch S-2 (Fig. 16) except for the plate circuit. The plate is connected through a 500 microhenry coil in series with a .047K resistor, to a power supply of +150 volts and through the same 500 microhenry coil, in series with .05 microfarad condenser to ground. The 500 microhenry coil is shunted by two germanium diodes connected in series. This switch operates, so far as inputs are concerned, in a manner identical to that described above for the switch S-2. However, the plate circuit is that of a peaker and the output at output terminal 7 is a sharp negative pulse. The diodes, shunting the 500 microhenry coil, clamp the oscillations of the coil, so that only the first negative pulse appears at the output terminal 7.

Fig. 19 illustrates an inverter type I-1. The plate of the left half of the dual triode is connected directly to an output terminal 7 and through 7.5K and 13K resistors to a power supply of +150 volts. The left grid is connected through a 1K resistor and a 470K resistor

to a power supply of -250 volts and through the same 1K resistor and a 200K resistor to the input terminal 5. The right half has an identical plate circuit, with the output taken from the terminal 6. However, the right grid is connected, through a 1K resistor and a 240K resistor, to a power supply of -250 volts and through the same 1K resistor and a 100K resistor, shunted by a 40 micro-microfarad condenser, to an input terminal 3, the cathodes are grounded. A positive signal input to terminal 5 produces a delayed negative output at terminal 7 and positive signal input to terminal 3 produces a negative output at terminal 6, with relatively no delay since the condenser passes the input signal with relatively no delay.

15 The inverter type I-3 is shown in Fig. 20. The left plate of the dual triode is connected through resistors of 3.9K and 3.3K values to a power supply of +150 volts, the output terminal 7 being tapped at a point between the two resistors. The left grid is connected 20 through a .47K resistor and a 20K resistor to ground, through the same .47K resistor and a 240K resistor to a power supply of -250 volts and through the same .47K resistor and a 47 micro-microfarad condenser to the input terminal 5. The cathode is grounded. A positive 25 signal input to the terminal 5 results in a negative pulse output at terminal 7. The right half of the tube has identical circuitry with an input terminal 3 and an output terminal 6.

30 The inverter I-5 shown in Fig. 21 also includes a dual 35 triode. The left plate is connected directly to an output terminal 7 and through a 12K resistor, in parallel with an 18K resistor, to a power supply of +150 volts. The left grid is connected through a .47K resistor in series 40 with a 330K resistor to a power supply of -250 volts and through the same .47K resistor in series with a 150K resistor, shunted by a 15 micro-microfarad condenser, to an input terminal 5. The cathode is grounded. This is a D. C. inverter and a signal input to terminal 5 is inverted and emitted from terminal 7. The right triode 45 has identical circuitry having an input terminal 3 and an output terminal 6.

50 The inverter I-6, illustrated in Fig. 22, uses a dual triode with each triode operating in parallel. The plates are connected directly to an output terminal 9 and 55 through a 2.2K resistor to a power supply of +150 volts. The grids are connected through separate 0.1K resistors, and a single 270K resistor, to a power supply of -250 volts, through the same 0.1K resistors and an 18K resistor, to ground and through the same 0.1K resistors and a 100 micro-microfarad condenser, to an input terminal 5. The cathodes are grounded. This is an A. C. inverter and a signal input to terminal 5 results in an inverted output pulse at terminal 9.

60 Fig. 23 illustrates the inverter I-7 which includes a dual triode. The plates have a common connection which leads directly to the output terminal 8, a further connection through an 0.15K resistor to ground and another through three .33K resistors in series to a power supply of +75 volts. The grids are connected through separate 0.1K resistors and a 270K resistor to a power supply of -250 volts, and through the same 0.1K resistor and a 500 micro-microfarad condenser to an input terminal 6. The cathode is connected, through a self-biasing circuit consisting of an 0.3K resistor, shunted by an .02 micro-microfarad condenser, to a power supply of -250 volts. A sharp positive pulse input to terminal 6 results in a sharp negative output at terminal 8.

65 A crystal controlled oscillator F is illustrated in Fig. 24 which comprises a pentode whose plate is connected through an 0.5 millihenry coil, shunted by a 10 to 100 micro-microfarad variable condenser, to a +300 volt power supply. The screen grid is connected through a 47K resistor to this power supply of +300 volts and through an .01 microfarad condenser, to ground. The control grid is connected to ground, through a crystal,

which is shunted by a 1000K resistor. The suppressor and the cathode are connected together and through an 0.25K resistor to ground. The circuit is tuned and controlled by the crystal so that the entire circuit oscillates at a frequency of one megacycle and the output is taken from terminal 9, which is connected to the cathode. 5

In the particular embodiment of this invention, to be described below, a defined time cycle is divided into periods having various numbers of one-microsecond intervals. The timing diagrams of Figs. 28 through 33 show that a complete cycle designated a character cycle, is divided into groups of "G" periods, "R" periods and "W" periods. These periods may have the following significance when used with an electronic storage device: 10

During the "R" times, information may be read from the device, during "W" times, information may be written in or stored in the device, and during "G" times, the information stored, may be re-generated. The smallest subdivision of the timing chart represents an interval of one microsecond. 15

It may be seen by inspection of the timing diagram that there is a period of 5 microseconds (each subdivision, as indicated at the top of each Fig. 28 through 34, being one microsecond) from G0 to G1, from R0 to R1, and from W0 to W1. There are periods of 9 microseconds from G1 to G2, G2 to G3, G3 to G4, and G4 to R0; 4 microseconds from R1 to R2, R2 to R3, R3 to R4, R4 to R5, R5 to R6, R6 to R7 and R7 to W0; 7 microseconds from W1 to W2, W2 to W3, W3 to W4, W4 to W5, W5 to W6, W6 to W7, W7 to G0. 20

Figs. 25, 26 and 27 taken together, show the circuits mainly in block form, for generating various signals, according to the requirements of the timing chart. 25

At the start of operation, the triggers 122 (Fig. 26) and 61 (Fig. 25) are reset to "on" conditions, while all other triggers are reset "off." The reset circuit is not shown but the setting of the triggers may be accomplished by any one of several well known means, for example, by delaying the application of the -250 volt bias supply (see Figs. 3 through 6) to the left grid of triggers 122 and 61 and to the right grid, of all the other triggers. The oscillator 30 (Fig. 25) is oscillating at a one megacycle rate and the output therefrom, is fed through the inverter 31, the peaker 32, the cathode follower 33 and the inverter 34 to line 435. Line 435 feeds a series of pulses (see line 435 of the timing diagram, Fig. 33) to the input terminal 6 of triggers 61, 62, 63, 64, 65, 67, 68, 69, 70, 71, 72, 73 and 74. These triggers are connected in cascade to form a main chain, each stage of the chain having two conditions of stability. Under the assumed conditions, the trigger 61 is in an "on" condition while all other stages of the chain are in "off" conditions. The first negative excursion of the signal (trailing edge) on line 435 shifts the trigger 61 "off" but has no effect on the other triggers of the chain, the latter triggers already being "off." As the trigger 61 shifts "off," a negative output is developed at terminal 8 and is fed to terminal 3 of trigger 62, which shifts 62 "on." 30

As trigger 62 shifts "on," a positive signal is emitted from its terminal 8 to the input terminal 3, of trigger 63, but it has no effect, since the diode in the input circuit (see Fig. 3, for example), blocks passage of positive signals. The next negative going signal on line 435, occurring one microsecond after the first, shifts trigger 62 "off," in turn, shifts trigger 63 "on." Thus, successive signals on line 435 cause the operation of the chain of triggers to progress, by shifting the "on" condition from one trigger to the next, in each of the successive triggers of the chain. For reasons that will be better understood later, trigger 61 is called the "9" stage of the chain, trigger 62 is the "8" stage, trigger 63 the "7" stage, trigger 64 the "6" stage, trigger 65 the "5" stage, trigger 67 the "4" stage, trigger 68 the "3" stage, trigger 69 the "2" stage, trigger 70 the "1" stage, trigger 71 the "0" or index stage, trigger 72 the "+1" stage (signifying one micro- 35

second after the "0" or index time), trigger 73 the "+2" stage, and trigger 74 the "+3" stage. 40

The outputs of the triggers are made available at the following points: Trigger 61 through cathode follower 50 to line 422, trigger 62 through cathode follower 51 to line 423, trigger 63 through the cathode follower 52 to line 424, trigger 64 through the cathode follower 41 to line 425, trigger 65 through cathode follower 53 to line 426, trigger 67 through cathode follower 54 to line 427, trigger 68 through cathode follower 55 to line 428, trigger 69 through cathode follower 42 to line 429, trigger 70 through cathode follower 56 to line 430, trigger 71 through cathode followers 57 and 44 to line 431, trigger 72 through cathode follower 58 to line 432, trigger 73 through cathode follower 59 to line 433, and trigger 74 through cathode follower 60 to line 434. These outputs on the various lines are shown on the timing diagram with corresponding numbers and will be referred to below as the outputs of the triggers. 45

After the start of operation as described above, and as the "on" condition is stepped from the trigger 70 to trigger 71, the cycle has reached G time (see timing diagram). The leading edge of the negative pulse output from terminal 7 of trigger 71 is fed through the cathode follower 57, the peaker 36, the cathode follower 37 and line 37A to terminals 3 of switches 80, 82, 83, 85, 86, 88, 89, 90, 91, 92, 93 and 95. At the G0 time, under the reset condition previously mentioned, the trigger 122 (Fig. 26) is in an "on" condition. The output of trigger 122 terminal 7 is available via cathode follower 114 and line 401. Its other output terminal 8 is then positive and is fed through the cathode follower 118, the inverters 105 and 106 to terminals 6 of the switches 86 and 88. The switches 86 and 88 are "conditioned" by the latter input and the pulse occurring on common input line 37A at the G0 time, is passed through these conditioned switches. The output from terminal 7 of switch 88 is negative and is coupled through 33 micro-microfarad condenser 87 to terminal 5 of the trigger 65, the latter being thus shifted "on." 50

At the same time, the output of switch 86, terminal 7 is fed via line 86A to terminal 6 of trigger 122, shifting the latter "off." The output of trigger 122 terminal 7 goes positive and is fed via the inverter 117 to terminal 3 of the trigger 120, shifting that trigger "on." The trigger 120 terminal 8 goes positive and via line 120A and inverters 101 and 102, conditions the switches 80 and 82. The output of trigger 120 terminal 7 goes negative and via line 120B turns "on" the trigger 162. 55

Therefore, during the first microsecond, after the G0 index time, triggers 120, 162, 65 and 71 are "on" while all other triggers are "off." The switches 80 and 82 remain conditioned, as long as the trigger 120 is "on." 60

The next impulse on line 435 occurs during this first microsecond after G0 time. The negative excursion (the trailing edge) steps the "on" condition from the "5" stage trigger 65 to the "4" stage trigger 67 and from the "0" stage trigger 71 to the "+1" stage trigger 72. However, the shifting of the conditions of the triggers are not completed, due to circuit delays until the end of the microsecond divisions shown on the timing diagram. Therefore, the outputs of trigger 65 and 71 (lines 426 and 431 of the timing diagram) are one microsecond negative signals occurring immediately after G0 time. 65

The stepping action continues and for the second microsecond after G0 time, triggers 67 and 72 are "on," then triggers 68 and 73, etc., until trigger 71 is again turned "on." The operation of the device has now progressed to the G1 time. 70

The negative output from trigger 71 terminal 7 again passes through the cathode follower 57, the peaker 36 and the cathode follower 37 to line 37A. As described above, the trigger 120, via line 120A and inverters 101 and 102 is conditioning the switches 80 and 82. The signal, now present on line 37A, passes through the 75

switch 82 and the 33 micro-microfarad condenser 81 to shift the trigger 61 "on" and also through the switch 80 and the cathode follower 96 to line 96A.

Triggers 142, 150, 156 and 162 are connected as a chain similar to the main chain described above, and the signal now present on line 96A serves to step the "on" condition from one trigger to the next succeeding trigger. As explained above, trigger 162 was turned on at G0 time, and therefore, trigger 162 is now at G1 time, turned "off" and trigger 156 is turned "on." The output of trigger 162 terminal 7, negative from G0 to G1 time, but now positive is fed through the cathode follower 163 to line 402. A plot of this output is also shown on the timing diagram.

The main chain continues to be stepped from the "9" stage trigger 61 on and requires nine microseconds before another negative output is available from the trigger 71. Inspection of the timing diagram shows that this output occurs at G2 time and after passing through circuitry, previously described, to line 37A, it reaches switches 80 and 82. Since the trigger 120 is still "on," the switches 80 and 82 are conditioned. The output from switch 82 again shifts the trigger 61 "on" while the output from switch 80 via the cathode follower 96 and line 96A steps an "on" condition from trigger 156 to trigger 150. Trigger 156 has been "on" from G1 to G2 time and its output is available via cathode follower 157 and line 403.

The main chain continues to be stepped. At G3 and G4 times, through the circuits and under conditions just explained, the "9" stage trigger is set to an "on" condition and the sub-chain receives stepping signals. At G3 time, the "on" condition is stepped in the sub-chain from trigger 150 to trigger 142. However, at G4 time, when trigger 142 is shifted "off," a signal is emitted from its terminal 8 via line 142A to turn "off" the trigger 120 and to turn "on" the trigger 123. The trigger 120 being "off," removes conditioning from the switches 80 and 82. The trigger 123, now "on" emits a positive output from its terminal 8 via cathode follower 115 and inverters 107 and 108 to condition the switches 89 and 90. The output of trigger 123 terminal 7 is available via cathode followers 130 and 131, and line 406.

Nine microseconds later at R0 time, as the main chain completes another cycle, the signal from trigger 71 reaching line 37A passes through the now conditioned switches 89 and 90. The output from switch 90 via the 33 micro-microfarad condenser 87 resets the "5" stage trigger 65 to an "on" condition. The output of switch 89 output 7, via line 89A turns "off" trigger 123. The output of trigger 123 terminal 8 via the cathode follower 115 and line 115A turns "on" the trigger 125 and via the same cathode follower 115 and inverters 107 and 108 removes the conditioning from the switches 89 and 90.

The trigger 125 now "on" emits a positive signal from terminal 8 via line 125A and inverters 111 and 112 to condition the switches 93 and 95 and a negative signal from terminal 7 via line 125B turns "on" trigger 178. Trigger 178 is the first stage of a "second" sub-chain comprised of triggers 178, 174, 170, 166, 160, 154 and 147. The outputs of this "second" sub-chain are available as follows: trigger 178 via cathode follower 179 and line 407; trigger 174 via cathode follower 175 and line 408; trigger 170 via cathode follower 171 and line 409; trigger 166 via cathode follower 169 and line 410; trigger 160 via cathode follower 161 and line 411; trigger 154 via cathode follower 155 and line 412; and trigger 147 via cathode follower 149 and line 413.

Five microseconds later, at R1 time, the output of trigger 71 reaching line 37A passes through the conditioned switches 93 and 95. The output of the switch 95 via the 33 micro-microfarad condenser 94 turns "on" the "4" stage trigger 67, while the output of switch 93 via cathode follower 98 and line 98A steps the second

sub-chain, to turn "off" trigger 178 and turn "on" trigger 174.

This operation, of resetting the "4" stage trigger 67 to an "on" condition and stepping the "on" condition along the second sub-chain, is repeated at R2, R3, R4, R5 and R6 and R7 times. However, at R7 time, as the trigger 67 is set to an "on" condition, the trigger 147 is turned "off" and the output of its terminal 8 via line 147A, turns "off" trigger 125 and turns "on" trigger 124. Trigger 125, going "off," removes the conditioning from the switches 93 and 95, while the output of trigger 124, terminal 8, via cathode follower 116, inverters 109 and 110 and line 110A, conditions the switches 91 and 92. The output of trigger 124 terminals 7 is available via cathode follower 133 and line 414.

Four microseconds later, at W0 time, the trigger 71 is turned "on" and the resulting signal on line 37A passes through switches 91 and 92. The output of switch 92 via the 33 micro-microfarad condenser 87, sets the "5" stage trigger 65 to an "on" condition, while the output of the switch 91, via line 91A, turns "off" the trigger 124. The trigger 124 going "off," removes the conditioning signal from the switches 91 and 92 and its output at terminal 8 via line 124A, turns "on" the trigger 121. The output of trigger 121 terminal 8, via inverters 103 and 104, now conditions the switches 83 and 85, while the output of terminal 7 via line 121A turns on the trigger 176 which is the first stage of a "third" sub-chain, including triggers 176, 172, 168, 164, 158, 152 and 144. The outputs of these triggers are available as follows: trigger 176 via cathode follower 177 to line 415, trigger 172 via cathode follower 173 to line 416, trigger 168 via cathode follower 169 to line 417, trigger 164 via cathode follower 165 to line 418, trigger 158 via cathode follower 159 to line 419, trigger 152 via cathode follower 153 to line 420, and trigger 144 via cathode follower 146 to line 421.

The next index time W1, occurs five microseconds after W0 time, and the signal on line 37A passes through the switches 83 and 85. The output of switch 85 via the 33 micro-microfarad condenser 84 sets the "7" stage trigger 63 to an "on" condition, while switch 83 emits a signal, via cathode follower 97 and line 97A to step this third sub-chain, specifically, at W1 time, to turn "off" trigger 176 and turn "on" trigger 172.

This operation is repeated every seven microseconds, at index times of W2, W3, W4, W5 and W6. However, at W7 time, the trigger 144 goes "off" and its output from terminal 8 via the cathode follower 141 and line 141A turns "off" trigger 121 and turns "on" trigger 122. Trigger 121, going "off," removes conditioning from switches 83 and 85 while trigger 122, terminal 8, now conditions, via the cathode follower 118 and inverters 105 and 106, the switches 86 and 88. Seven microseconds later the index point of G0 is again reached and the entire operation may be repeated. The conditions now existing are the same as those existing and described at the previous G0 time.

It may be desirable during certain types of operations, to remain in regeneration or the "G" portion of the cycle and during such times, a positive signal applied to line 126A (Fig. 26) causes the system to operate as follows: As the cycle progresses to the R0 index time, a positive signal on this line 126A passes through the inverter 126 to terminal 8 of the trigger 125. This signal to terminal 8, "clamps" the trigger 125 in an "off" condition, and the signal at R0 time, normally arriving at pin 3, from trigger 123, via the cathode follower 115, has no effect. The positive signal on line 126A also conditions the switch 132. Therefore, as the trigger 123 goes off (at R0 time) a signal is emitted from its pin 7 via the cathode follower 130 and the now conditioned switch 132, to turn "on" the trigger 120. As trigger 120 goes "on," the same conditions prevail that exist a fraction of a microsecond, after G0 time. Therefore, the operation of the cycle is switched,

from R0 time to G0 time, and as long as the potential of line 126A is positive, the system repeats the "G" portion of the cycle and this portion only.

It should be noted that the triggers in the main chain, to the left of the index or "0" stage (trigger 71) assume "on" conditions, before this index time by a number of microseconds corresponding to the stage number. However, a trigger assumes an "on" condition only when the number of microseconds in the interval between index points is equal to or in excess of the stage which a particular trigger represents. For example, the "9" stage trigger 61 is "on" for a period of one microsecond starting "9" microseconds before the index times of G2, G3, G4 and R0.

The triggers 72, 73, and 74 to the right of the index stage, respectively assume "on" conditions one, two and three microseconds after each index point, regardless of the number of microseconds between the index points. The signals shown on lines 401 through 435 of the timing diagram and available on corresponding lines of the circuit diagram may be utilized to develop any desired signals or series of signals.

One example of means for producing such signals is shown in Fig. 36. The signal on line 403, going negative at G1 time, is fed to terminal 3 of trigger 501, turning it "on." The signal on line 406, going negative at G4 time, is fed to terminal 6 to turn "off" the same trigger. The output from terminal 8, positive from G1 to G4 time, "conditions" the switch 502 terminal 6. The signals on line 434, one microsecond pulses occurring three microseconds after the index times are fed via the inverter 503 to terminal 3 of the switch 502 and cause conduction during the time the switch is "conditioned." The output from terminal 7 on line 436 is a series of three, one microsecond pulses occurring at G1-3 (D1) (meaning a signal starting three microseconds after G1 time and having a duration of one microsecond) G2-3 (D1) and G3-3 (D1) times.

Figure 37 illustrates circuits for the development of an R1-1 (D1) signal. The signal on line 408, negative from R1 time to R2 time, passes through the inverter 504, to "condition" the switch 506 terminal 6. The pulses on line 428, occurring three microseconds before each index time, are fed through the inverter 505 to terminal 3 of the switch 506. Only one of the latter pulses, that is the one occurring between R1 time and R2 time, passes through this switch. The output then is a one microsecond pulse occurring three microseconds before R2 time or an R1-1 (D1) signal.

While certain types of triggers, peakers, cathode followers, switches, etc., have been illustrated, obviously many other types may be employed in the novel arrangement disclosed and described.

While there have been shown and described and pointed out the fundamental novel features of the invention, it will be understood that various omissions and substitutions and changes in the forms and details of the device illustrated and in its operation may be made by those skilled in the art, without departing from the spirit of the invention. It is the intention, therefore, to be limited only as indicated by the scope of the following claims.

What is claimed is:

1. A chain of triggerable elements operable in a major cycle of operation, each major cycle comprising a plurality of minor cycles and means for changing the time duration pattern of the minor cycles, said means comprising means counting the number of minor cycles, and means operatively responsive to said counting means for controlling the number of said triggerable elements operable in said chain during each minor cycle.

2. A chain of bistable triggerable elements operable in a major cycle of operation, each major cycle comprising a plurality of minor cycles, and means for changing the time duration pattern of the minor cycles, said means comprising means counting the number of minor cycles,

and means operatively responsive to said counting means for controlling the number of said bistable triggerable elements operable in said chain during each minor cycle.

3. A chain of bistable trigger elements, said bistable trigger elements connected in cascade and operable in a major cycle of operation, each major cycle comprising a plurality of minor cycles, said chain completing a cycle of operation during each minor cycle, means for changing the time duration pattern of the minor cycle, said means comprising means counting the completed minor cycles, and means operatively responsive to said counting means for controlling the number of bistable trigger elements operable in said chain during each minor cycle.

4. A chain of bistable triggers connected in cascade and operable in a major cycle of operation, each major cycle comprising a plurality of minor cycles, said chain completing a cycle of operation during each minor cycle, means for changing the time duration pattern of the minor cycles, said means comprising a plurality of counters counting the minor cycles and means operatively responsive to said counters controlling the number of triggers operable in said chain, means initiating a first counter of said plurality of counters, said first counter taking control whereby a certain number of triggers are operable in said chain, a second counter initiated by the first counter after the latter has counted a certain number of minor cycles, the second counter thereby taking control to change the number of triggers operable in the ring.

5. An electronic circuit for distributing signals according to a pattern, comprising a chain of bistable triggers connected in cascade, at least one of said triggers being set to an "on" condition of stability, means periodically stepping the "on" condition from one trigger to a next succeeding trigger, means coupling between two of said triggers to close the chain, said closed chain including a predetermined number of triggers and completing a cycle of operation as an "on" condition is stepped through each one of the predetermined number of triggers, means counting the number of cycles completed by said closed chain, said coupling means being operatively responsive to said counting means to change the number of triggers in the closed chain when a certain number of cycles have been completed.

6. An electronic commutator for distributing signals of an input signal source according to a prearranged pattern, comprising a chain of bistable triggers having interconnections for transferring an "on" condition from one trigger to a succeeding trigger, at least one of said triggers being set to an "on" condition, said input signals transferring the electrical "on" condition of a trigger to a succeeding trigger, said chain being closed by intercoupling between a terminating trigger and a first starting trigger, said chain emitting a predetermined number of intermediate signals and a principal signal, as the chain is stepped through a cycle, a counter counting said cycles, said counter emitting an output when a predetermined number of cycles are completed, and means operatively responsive to said counter output to couple the terminating trigger to a different starting trigger whereby the number of intermediate signals emitted in each cycle is changed.

7. An electronic commutator for distributing signals of an input signal source according to a prearranged pattern comprising a chain of bistable triggers having interconnections for transferring an "on" condition from one trigger to a succeeding trigger, one of said triggers being reset to an "on" condition, said input signals transferring the electrical "on" condition of a trigger to a succeeding trigger, said chain being formed into a closed ring by intercoupling between a terminating trigger and a first starting trigger, said ring emitting a number of intermediate signals and a principal signal, as the ring is stepped through a cycle, the total number of signals in one cycle being equal to the number of triggers in the ring, a counter counting said principal signals and emitting

an output when a predetermined number of cycles are completed, and means operatively responsive to said counter output to couple the terminating trigger to a different starting trigger whereby the number of intermediate signals emitted in each cycle is changed.

8. An electronic circuit for distributing signals of an input signal source according to a prearranged pattern comprising a closed ring of a number of bistable triggers, means causing the operation of the triggers, one trigger after the other in sequence, means counting the number of cycles executed by said ring, and means responsive to said counting means for changing the effective number of triggers in said ring.

9. An electronic circuit for distributing signals of an input signal source according to a prearranged pattern comprising a closed ring of a number of bistable triggers, means including said input signal source causing the operation of the triggers, one trigger after another in sequence, means counting the number of cycles completed by said ring, and means responsive to said counting means for changing the effective number of triggers in said ring.

10. An electronic circuit for distributing signals of an input signal source according to a prearranged pattern comprising a number of bistable triggers connected in cascade in an endless chain, means including said input signal source causing the operation of the triggers, one trigger after another in sequence, means counting the number of cycles completed by said chain, and switching means responsive to said counting means for changing the effective number of triggers in said chain.

11. An electronic device comprising a chain of electronic elements connected in cascade, means initiating sequential operation of said elements in seriatim, said elements completing a cycle of operation as the sequential operation is stepped through a predetermined number of said elements, and means for automatically initiating a partial sequential operation of said elements, beginning at an intermediate element in said chain.

12. A device as in claim 11, and including means for automatically repeating said partial operation of said chain.

13. A device as in claim 11, and including means for automatically initiating a second partial operation or a complete operation of said chain.

14. A device as in claim 11, and including means for

automatically initiating a partial or full operation of said chain beginning at an element in said chain, other than said intermediate element.

15. A device as in claim 11, and including means for automatically initiating a partial operation of said chain beginning at an element in said chain behind said intermediate element.

16. A chain of bistable trigger elements connected in cascade and individually operable to an "on" or "off" condition and at least one of said triggers being set to an "on" condition of stability, means stepping the "on" condition from one trigger to a next succeeding trigger, means coupling two of said triggers to close the chain, said closed chain including a predetermined number of triggers and completing a cycle of operation as the "on" condition is stepped from a starting trigger through intermediate triggers to a terminating trigger, and means automatically initiating a partial operation of said chain beginning at one of said intermediate triggers.

17. A chain of bistable trigger elements connected in cascade and individually operable to an "on" or "off" condition and at least one of said triggers being set to an "on" condition of stability, means stepping the "on" condition from one trigger to a next succeeding trigger, said chain including a predetermined number of triggers and completing a full cycle of operation as the "on" condition is stepped from a starting trigger through intermediate triggers to a terminating trigger, means automatically setting one of said intermediate triggers to an "on" condition to initiate a partial cycle of operation, and means automatically repeating said partial cycle of operation or initiating a full or partial cycle of operation beginning at a trigger in said chain other than one of said intermediate triggers.
